UNITED STATES PATENT OFFICE.

PETER ASTRYKE, OF ALEXANDRIA, VIRGINIA, ASSIGNOR OF ONE-HALF TO
JOHN S. BORDNER, OF ALEXANDRIA, VIRGINIA.

JAR-CLOSURE.

SPECIFICATION forming part of Letters Patent No. 728,830, dated May 26, 1903.

Application filed August 16, 1902. Serial No. 119,954. (No model.)

To all whom it may concern:

Be it known that I, PETER ASTRYKE, a citizen of the United States, residing at Alexandria, in the county of Alexandria and State 5 of Virginia, have invented a new and useful Improvement in Jar-Closures, of which the following is a specification.

This invention relates generally to jar-closures, and more particularly to one adapted 10 for use in connection with milk-jars now in common use. These milk-jars are usually closed by means of a flat paper disk which is inserted into the mouth and held therein by frictional contact. Considerable difficulty 15 has been experienced in removing this disk from the mouth of the milk bottle or jar, and various means and devices have been provided for removing the said disk; but, so far as I am aware, all such means and devices 20 have been subject to one objection or another. It is therefore with the object of providing a simple and efficient means which shall not materially add to the cost of the disk that I have devised my present invention.

25 The invention consists, essentially, in arranging a string or tape beneath the top layer of the disk and passing the free end of said string or tape up through an aperture produced in the said upper-layer.

30 The invention consists also in reinforcing the said aperture, so as to avoid tearing or mutilating said upper-layer.

The invention consists also in certain details of construction hereinafter described, 35 and pointed out in the claims.

In the drawings forming a part of this specification, Figure 1 is a perspective view of a milk-bottle having a cap applied thereto constructed in accordance with my invention.

40 Fig. 2 is a sectional view of the said cap arranged in the mouth of the bottle or jar. Fig. 3 is a detail perspective view of the said cap. Figs. 4 and 5 show details of construction. Fig. 6 is a detail perspective view of a cap, 45 showing a different arrangement of the puller. Fig. 6^a is an enlarged detail section of the same. Figs. 7, 8, 8^a, and 9 illustrate further modified forms of pulling loops or strings.

Referring to the drawings, A indicates the 50 ordinary milk-bottle, and B the paper cap or disk, which fits into the mouth thereof. This

disk is made of paper and comprises two or more layers, as preferred. In the present instance I have shown the disk as composed of two layers—the upper one, B', and the lower one, B²—and between the said layers B' and B² is secured a string or tape C, the free end of which passes up through a perforation B³, produced in the upper layer, adjacent to the edge of the same, and in practice I prefer to 60 have the said perforation reinforced by a supplemental layer B⁴, said reinforcement greatly strengthening the edge of the perforation, and thereby preventing the layer being torn or mutilated at that point whenever a strain 65 is placed upon the string or tape. In operation the disk or cap is fitted into the mouth of the bottle by pressing downwardly upon the same in the usual manner, and the said disk or cap is held therein by a frictional 70 contact. When it is desired to remove the said disk or cap, it is only necessary to pull the string or tape and said disk or cap will be lifted out of the mouth of the bottle or jar; but inasmuch as the said pull is ex- 75 ereted at a point adjacent to the edge the disk or cap will be easily removed, and as the perforation in the upper layer is reinforced 80 it is obvious that all tearing at that point will be entirely avoided, and the pull upon 85 the string will therefore be sufficient to quickly and easily remove the cap without damaging same. It will also be noted that the cord or tape never comes in contact with the contents of the bottle or jar, and, furthermore, the said cord or tape being soft and flexible will not injure the hands of the person opening the bottle or jar.

While I have stated that I prefer to employ a string or tape, I may use wire or wire 90 and cord or tape, as shown in Figs. 6 to 9, inclusive.

In Figs. 6 and 6^a I show a pulling-loop C', that is hinged to a wire or cord c², that is securely held between the layers of the cap, 95 said pulling-loop projecting through the perforation and reinforcement B⁴, and is arranged to fold down against the cap, as shown in dotted line in Fig. 6^a.

In Fig. 7 the loop C² is fixed and the ends 100 held between the layers of the cap, and in Figs. 8 and 8^a I show a combination of cord and

wire in which the cord or tape C³ is secured to a wire, which is also held between the layers of the cap, while in Fig. 9 a fixed metallic loop is employed and in which the ends of the said loop are passed through the reinforcement surrounding the eye and held between the layers of the cap, as clearly shown in dotted lines.

It will thus be seen that I provide an exceedingly cheap, simple, and efficient construction of jar-closure, which will remedy all of the defects to which the present constructions are subject.

Having thus fully described my invention, what I claim as new, and desire to secure by Letters Patent of the United States, is—

1. A jar-closure comprising a disk composed of a plurality of layers, the upper layer being perforated and a string or tape secured between the said layers, one end of said string or tape being passed upward through the perforation.

2. A jar-closure comprising a disk composed of a plurality of layers, the upper layer

being perforated, said perforation being surrounded by reinforcements and a string or tape secured between the layers, one end of said string or tape, being passed through the reinforced perforations.

3. A jar-closure consisting of a disk composed of a plurality of layers, the upper layer having a perforation adjacent to the edge, the edges of said perforation being reinforced upon the exterior of the layer and a string or tape secured between the layers one end of said string or tape passing upwardly through the reinforced perforations, as specified.

4. A jar-closure comprising a disk formed of layers, the upper layer being perforated adjacent one side, the edges of said perforations being reinforced on each side of said disk, and a pull member secured between the layers and projected upward through the reinforced perforation.

PETER ASTRYKE.
